UNITED STATES PATENT OFFICE.

JAMES POLLITZ AND EDWARD HY. COX, OF NEW YORK, N. Y.

MEANS FOR LAUNCHING LIFE-BOATS FROM VESSELS.

SPECIFICATION forming part of Letters Patent No. 634,028, dated October 3, 1899.

Application filed October 27, 1898. Serial No. 694,677. (No model.)

To all whom it may concern:

Be it known that we, JAMES POLLITZ, a subject of the Emperor of Germany, but having declared my intention of becoming a citizen 5 of the United States and taken my first papers for such purpose,) and EDWARD HY. COX, a subject of the Queen of England, both residing in the borough of Manhattan, city of New York, county and State of New York, 10 have invented certain new and useful Improvements in Means for Launching Life-Boats from Vessels, of which the following is a specification.

The invention relates especially to the construction and arrangement of the davits which support life-boats over the decks of ships or other vessels and from which they are lowered into the water for preserving life in case of shipwreck or disaster.

20 The object is to construct means for supporting and lowering such boats with expedition and launching them in the water at a sufficient distance from the vessel on which they are carried as to be more free than heretofore 25 from the motion or wash of the sea against the ship.

To this end the invention consists in providing suitable supporting-davits, which are hinged or pivotally attached to the side of the 30 vessel a short distance above the water-line, said davits being adapted to swing a life-boat outwardly and launch the same away from the vessel the distance of their length and to turn the boat at an angle to the side of the 35 vessel, as hereinafter more fully described, and pointed out in the claim.

In the drawings, Figure 1 is a perspective view of a portion of a vessel, showing a life-boat on one side thereof in position on the 40 deck and another lowered into the water on the opposite side, but connected with the davits by which it is supported and launched. Fig. 2 is a plan view of the same, showing by dotted lines the position of the life-boat when 45 at rest and secured on the deck and by full lines its position when lowered into the water. Fig. 3 is a side view of a portion of a vessel with the davits in an upright position and the life-boat at rest and secured over the deck, 50 while Figs. 4 and 5 are details of blocks or castings attached to the side of the vessel and provided with lugs having apertures for re-

ceiving a pin or bolt by which the forked end of the davit may be hinged or pivotally secured to the same. Fig. 6 shows the lower 55 forked end of one of the davits.

In the drawings, A represents a vessel; a a, the supports for a life-boat B when at rest above the deck, and to which it is secured in the usual manner by wedges or keys b b. The 60 life-boat is connected by suitable tackle c c to the upper end of the davits C C, which also connect by suitable tackle with the guys d d for raising and lowering the same. The davits C C are preferably provided with forked 65 ends e, which are hinged or pivoted to the lugs f on the castings D, secured to the side of the vessel at a point not far from the water-line—say three or four feet above the same. The davits C C extend upward along 70 the side of the vessel and far enough above the edge of the same to support a life-boat in the usual place and position, and the means by which it is secured need not vary from those ordinarily in use for such purposes; but 75 the davits need not have the usual curve at the top, as the life-boat may be swung inwardly over the deck by the tackle c c, as shown in Fig. 1.

We form the hinge or pivotal connection 80 for the lower end of one of the davits so that it will swing outwardly at a different angle to the side of the vessel from the other one, and thereby give the bow of the life-boat an outward turn during its lowering and launching. 85 This movement will greatly facilitate the rowing at the outset and occasion less delay than that which ordinarily occurs when the life-boat is lowered parallel to the vessel and receives the wash broadside which makes difficulty in starting the rowing. 90

As the means by which the lowering and launching is effected brings the life-boat at a considerable distance from the edge of the vessel, especially large vessels requiring long 95 davits, those who are in it will be subjected to less danger of loss by the movements of the vessel or of the water than when launched in the usual way.

Another advantage of this means for supporting and launching such boats is that they can be lowered from either side of the vessel, which has not heretofore been usual nor always possible, owing to the fact that fre-

quently the vessel is inclined too much to one side to permit any attempt at launching on the other.

Having thus described our invention, what we claim as new, and desire to secure by Letters Patent, is—

A life-boat-launching apparatus comprising two davits, pivotally secured to the side of a vessel, the connection being such as to cause one of them to swing outwardly at a

different angle to the side of the vessel from that of the other, in combination with means for connecting a life-boat to the free ends of said davits, and for manipulating the same while being lowered, substantially as set forth. 15

JAMES POLLITZ.

EDWARD HY. COX.
